CLAIM

The ornamental design for a wireless charger, as shown and described.

DESCRIPTION

1. Wireless charger

1.1: Front

1.2: Back

1.3: Left

1.4: Right

1.5: Top

1.6: Bottom

1.7: Perspective

1.8: Perspective

1.1 is a front view of a wireless charger showing my new design;

1.2 is a back view thereof;

1.3 is a left view thereof;

1.4 is a right view thereof;

1.5 is a top view thereof;

1.6 is a bottom view thereof; and

1.7 and 1.8 are two perspective views thereof.

(Continued)

The broken lines shown in the drawings illustrate portions of the wireless charger that form no part of the claimed design.
